AUTOMOBILE

William F. Victor, Skokie, Ill.

Application June 6, 1958, Serial No. 51,222

Term of patent 7 years

(Cl. D14—3)

Fig. 1 is a perspective view of an automobile, showing my new design, the rear of which is conventional and is shown broken away for convenience of illustration; and

Fig. 2 is an enlarged fragmentary front view of Fig. 1.

In Fig. 2, the drawing is lined for contrasting colored areas of the dominant feature.

The essential features of my design reside in those portions shown in full lines.

I claim:

The ornamental design for an automobile, as shown and described.
